UNITED STATES PATENT OFFICE.

EDWARD E. HUSSEY, OF SANFORD, MAINE, ASSIGNOR TO SANFORD MILLS, OF SANFORD, MAINE, A CORPORATION OF MAINE.

DESIGN FOR A WOVEN PILE FABRIC.

54,091.

Specification for Design.

Patented Nov. 4, 1919.

Application filed February 28, 1918. Serial No. 219,705. Term of patent 7 years.

To all whom it may concern:

Be it known that I, EDWARD E. HUSSEY, a citizen of the United States, residing at Sanford, county of York, State of Maine, have invented a new, original, and ornamental

Design for a Woven Pile Fabric, of which the following is a specification, reference being had to the accompanying drawing, forming a part hereof.

The figure is a plan view of a section of woven pile fabric showing my new design.

The portions shown in dark color are depressed and the portions shown light are elevated.

I claim:

The ornamental design for a woven pile fabric as shown and described.

EDWARD E. HUSSEY.
